UNITED STATES PATENT OFFICE

WILLIAM W. SAYERS, OF CHICAGO, ILLINOIS, ASSIGNOR TO LINK-BELT COMPANY, OF CHICAGO, ILLINOIS, A CORPORATION OF ILLINOIS

AUTOMATIC CONTROL FOR SKIP BUCKETS

Application filed January 23, 1930. Serial No. 422,736.

My invention relates to improvements in skip hoists and has for one object to provide a new and improved control apparatus and process whereby the filling of the bucket may be more nicely controlled and whereby the pause or delay necessary at the end of the filling period to insure complete filling and guard against clogging of the material stream and the like may be avoided. Other objects will appear from time to time throughout the specification and claims.

Referring to such skip hoist as that shown in my Patent No. 1,583,702, dated May 4th, 1926, it will be noted that when the skip descends, causing the spout to swing down into discharge relation with the open mouth of the skip and causing the gate to open, material flows from the hopper through the fixed chute, the pivoted chute or spout into the skip until the material fills the skip. When it does, this material banks up in the pivoted chute and in the fixed chute. Then by the operation of any suitable control mechanism, the gate is closed and the spout or pivoted chute swings up as the skip goes up so that a part of the material left in the pivoted chute beyond the gate is discharged into the skip to complete the load.

Experience shows in connection with devices such as this that a considerable lag or delay must be provided to insure complete filling of the skip. If the material is dry and free flowing, it rushes in and fills the skip without delay and under those circumstances the skip could start up in a very few seconds after it gets down. On the other hand, we may have a material which is wet or there may be a bridge or partial bridge formed somewhere in the hopper or chute and it may require quite an appreciable time for the skip to fill. In order that the skip may not be carried up partially empty, it is common practice to set the automatic timing and controlling mechanism so as to provide for the longest necessary delay to take care of the slowest, most sluggish flowing material. This means over a days run, that where most of the times the skip might be loaded in a second or so, there may be a half dozen loads where they have to give ten seconds and

in order to be safe it is necessary to have every load take ten seconds. I propose to provide automatic means to control the loading operation such that the skip may start up just as soon as it is filled. I propose to control the automatic loading timing means by the actual flow or presence of material in the skip, or in the pivoted gate immediately adjacent the skip.

My invention is illustrated more or less diagrammatically in the accompanying drawings, wherein—

Figure 1 is a diagrammatic side elevation showing the skip empty.

Figure 2 is a similar view showing the skip full and about to start up;

Figure 3 is a similar view showing the skip after it has started up;

Figure 4 shows a modified form with the skip empty;

Figure 5 shows the device of Figure 4 with the skip full;

Figures 6 and 7 show a further modified form with the skip empty and full;

Figures 8 and 9 show a further modified form showing the skip empty and full.

Like parts are indicated by like characters throughout the specification and drawings.

Referring to Figures 1, 2 and 3, A is a track inclined though it might be vertical. Along this track travels a skip A¹ open at the top, a bail A², a hoisting cable A³ and wheels A⁴ A⁵ engaging the track. A hoisting engine of any suitable type is of course used to operate the skip and it is hoisted to some elevated position and then dumped and then returned.

B is a hopper having a fixed chute B¹, closed by an undercut gate B². Associated with the undercut gate is a pivoted chute B³ which when in the loading position is in alignment with the chute B¹ and discharges into the open mouth of the skip. The top of this chute is open but baffle plates B⁴ are provided to cause material to bank up against them and prevent spillage of material when material from the hopper flows down the fixed and pivoted chutes to fill the skip and bank up in it and in the chutes. The skip engages the pivoted chute and as it starts

up rotates the chute into the closed position, at the same time rotating the undercut gate to shut off flow though if desired the gate may be separately operated.

5 The lowermost of the baffle plates C instead of being fixed in the pivoted chute is pivoted therein. It is so positioned that it is located above the normal flow line of material as it flows freely down through the 10 fixed and pivoted chute from the hopper to the skip but as material piles up in the mouth of the skip and backs up in the chute, this flowing stream of material backs up against or impinges upon the pivoted baffle plate C, swings it to the right into the position shown in Figure 2, causing the tongue or lever C¹ to engage the roller C² on the switch C³ which switch controls a circuit through the cable C⁴ to the control panel to 15 start the motor operating the hoisting engine. C⁵ is a limit rod or stop associated with the bracket C⁶ to constrain the angular displacement of the member only within predetermined limits. It will be obvious from 20 this arrangement that as soon as the material backed up, the flowing material or the stream of material will build up to a point which impinges upon the baffle plate and causes operation of the switch but this 25 switch operation cannot take place until such backing up has occurred and since such backing up cannot occur until the skip is filled the hoisting engine will only be started when the skip is filled, thus avoiding delay.

30 35 In the modified form shown in Figures 4 and 5, everything is the same except that here we have a slightly different form of pivoted chute D with the undercut gate D¹ generally integral with the chute and with the chute closed above and discharging at its side rather than at its end into the skip. In 40 this arrangement the swinging plate D¹ is on the end of the chute and projects into the skip but at a point where it is not attacked by the stream of material until the bucket is 45 filled and material is backed up as shown in Figure 5; when the material is so backed up, the material swings the plate and causes the finger D² to engage the switch button D³ on the switch D⁴ to start the motor.

50 55 In the further modified form shown in Figures 6 and 7, the switch E is mounted on the bottom of the loader chute and the wall of the bucket with the control arm E² extending through the wall of the bucket in opposition to the switch lever E³. When the material backs up in the bucket itself not in the chute at all, switch operation takes place as shown in Figure 7. Of course, when the 60 bucket starts up the rotation of the chute moves the switch lever E³ out of the path of the finger on the swinging plate.

65 In the arrangement shown in Figures 8 and 9, a further modification is shown. Here the switch F is on a bracket removed from

the chute. The chute F¹ is fixed. There is no pivoted chute, only an undercut gate F². The swinging plate F³ is pivoted on the bucket. It has an arm F⁴ extending through a hole in the bucket to engage the switch lever F⁵. Here again the material piles up in the bucket to operate the switch to start the hoisting motor.

70 75 All of the arrangements above disclosed have one essential factor in common, namely, the switch is controlled by some kind of a member. It may be a swinging plate, it may be a push button, flexible diaphragm or anything else which feels the effect of the pressure or impact of the material when a sufficient quantity of material has piled up 80 into the bucket or backed up into the chute so that the bucket or skip is filled. Only when material has come in to this extent does this sensitive member feel the effect of the material and when it does feel it then and then only is it displaced to close the switch 85 to start the bucket hoisting motor.

90 95 Of course, a device such as this does not in any way interfere with the ordinary push button control and it can even be arranged in connection with a normal and predetermined time control if that is desirable.

100 105 My invention concerns itself only with what happens at the filling end of the bucket or skip excursion. While it may perhaps happen that under some conditions it takes longer to dump the skip than it does to fill it, my invention by reducing to a minimum the time necessary to delay the skip for filling makes possible a closer, more rapid method of control. If it should happen that the dumping was the longer of the two actions, no harm would be done and my control method would still be equally valuable as it would enable the designer to dismiss to some extent from his hand the time factor involving the 110 115 loading of the skip.

120 125 I have used the word bulk in a number of places in the specification and claim and it must be understood that I have used it in the strict sense distinguishing bulk or volume from weight. My control is responsive to the bulk or volume of material as distinguished from the mass or weight of material.

I claim:

130 135 The combination with a skip hoist; including a movable bucket, a combined pivoted chute and gate adapted at one point in the bucket path to discharge material thereinto and adapted in response to movement of the bucket away from the filling position to be rotated thereby to shut off the flow of material; of control means comprising a switch, and a switch operating member mounted in permanent relation to each other on the chute at a point above the path of flowing material in the chute the operating member being adapted to be displaced by the 140 145 pressure of material as it banks up in the

chute after the bucket is filled, to operate the switch and thereby cause movement of the bucket away from the filling point, there being a permanent electrical connection between the switch and the bucket operating mechanism.

Signed at Chicago, county of Cook, and State of Illinois, this 15th day of January, 1930.

WILLIAM W. SAYERS.
